UNITED STATES PATENT OFFICE

ALBERT R. HAAG, OF PEORIA, ILLINOIS

GEARING FOR WASHING MACHINE AGITATORS

Application filed July 29, 1925, Serial No. 48,718. Renewed July 19, 1930.

My invention relates to gearing for washing machine agitators.

An object of the invention is to provide an improved gearing for driving the agitator of a washing machine, with improved means for throwing said gearing into and out of gear, and for locking it in either position.

Other objects of the invention will appear in the following specification, taken in connection with the annexed drawings, in which—

Fig. 1 is a plan view of the device, with the lid portion broken away and disclosing in dotted lines the arrangement of operating gear parts and driving means below the bottom of a container or tub, also partially in transverse section to show operating means for effecting relative connection or disengagement of driving connection for an agitator member.

Fig. 2 is a side elevation, showing a container and parts connected therewith, said container being broken away to show interior operating parts, said interior operating parts being partially in section to better illustrate structure and arrangement of parts;

Fig. 3 is a detail plane view, showing an operating means for effecting engagement or disengagement of the gear parts;

Fig. 4 is a plan view of the same subject-matter as disclosed in Fig. 3, the parts being merely in different position;

Fig. 5 is a side elevation showing the same subject-matter as disclosed in Fig. 3, a portion in said figure being broken away in order to show detail parts.

Referring to the drawings, 10 refers generally to a circular container or tub; 13 are leg supports for the container, and 14 is a removable lid or cover.

The agitator structure is essentially the same as that disclosed in my prior Patent #1,563,624, issued December 1, 1925, and comprises an agitator member 15 having a base 16, baffles 17, and a shank 18 which is adapted to be driven by the agitator shaft 24. Shaft 24 is supported by bracket 25 and carries a gear 27 at its lower end.

28 is an arcuately fashioned rack or segmental gear related to gear 27 for optional

relative intermesh. 29 is a reach member connected with the rack centered and supported in conjunction with eccentric member 30, the latter being fixed to rod 31, said rod being supported at its opposed ends respectively in conjunction with bracket members 32 and 33. A shifting handle 34 is fixed to the upper portion of rod 31, and serves to turn the latter for the purpose of longitudinal reciprocation of reach member 29 to cause gear 27 to engage or release rack 28, to the end that driving member 24 may be reciprocated or, through disengagement with respect to said gear and rack, said driving member may be at rest. To facilitate permanency of placement of shifting lever 34, a spring lock is provided, including a spring and ball, as shown in Fig. 2, the same being adapted to engage, at option, a series of depressions in the lower face of bracket member 33.

The means for actuating the rack 28 includes pitman member 35, pivoted at one end to the rack, and at its opposed end to the crank member 36. Any suitable means may be employed to drive crank member 36.

Special attention is called to the clutch means herein shown that provides for optional relative engagement as between the gear on the driving member and a rack, which affords a simple and improved means for regulating such connection and reduces materially the wear that ordinarily attends such shift gear connection.

With respect to the manner of engagement of the pivoted segment gear with the driven gear attached to the agitator shaft, it will be noticed immediately that due to the eccentric mounting for the segment gear, when said segment is reciprocated and the eccentric moved to permit engagement of the segment with the driven gear, the teeth on the segment will move in a line tangential with reference to the axis of reciprocation of the driven gear.

What I claim is:

1. In a washing machine, a tub, a vertical agitator shaft having its lower end extending below said tub, a gear fixed to the lower end of said shaft, a rack member adapted to engage and actuate said gear, a movable eccen-

- tric member associated with said rack member in fixed pivotal relation, a lever for oscillating said rack, and means positioned adjacent the upper portion of said tub for rotating said eccentric member to thereby move said rack into and out of engagement with said gear.
2. In a washing machine, an agitator shaft, a gear fixed to the bottom of said shaft, an eccentric member movably mounted near the bottom of the machine, a rack member pivoted to said eccentric member and adapted to engage said gear, means for oscillating said rack, means comprising a shifting handle near the top of said machine for moving said eccentric member to thereby move said rack into and out of engagement with said gear, and means for locking said handle in either of two positions.
- 10 3. In a washing machine, a tub, an agitator shaft having one of its ends extending below said tub, a gear fixed to said end, an oscillating rack adapted to engage and actuate said gear, an eccentric member forming a pivot for said rack, means for oscillating said rack, and means for rotating said eccentric member to thereby move said rack into and out of engagement with said gear, said rotating means including a shifting handle positioned adjacent the upper portion of the tub.
- 20 4. In a washing machine, in combination, a tub, an agitator shaft having one end extending below said tub, a gear fixed to the lower end of the shaft, a segmental gear adapted to engage and actuate said gear, an eccentric pivotally mounted adjacent the lower outer edge of the tub forming a pivot for said segmental gear, means for oscillating said segmental gear, and a handle for pivoting said eccentric to move said segmental gear into and out of engagement with said gear.
- 30 5. In a washing machine, in combination, a tub, an agitator shaft having one end extending below said tub, a gear fixed to the lower end of the shaft, a segmental driving gear adapted to engage and actuate said gear, a rotatably mounted eccentric upon which said segmental gear is pivoted, means for oscillating said segmental gear and means for rotating said eccentric to move the segmental gear into and out of engagement with the driven gear comprising a handle mounted on a vertical shaft adjacent the outer edge of the tub and means connecting said handle with said eccentric.
- 40 6. In a washing machine, in combination, an agitator shaft, a pinion secured thereto, an arcuately shaped segmental driving gear adapted to be engaged with and disengaged from said pinion, a pivotal mounting for said segmental gear, a crank, a pitman connected at one end to said crank and at its other end pivoted to said segmental gear at a point outwardly disposed from the gear axis and an eccentric mounting for the pivot of the gear permitting the gear to be moved into and out of driving relation with said pinion, said eccentric and the pivotal connection between the pitman and segmental gear causing the segmental gear to have a compound movement radially and tangentially of the pinion during the engaging operation.
- 50 7. In a washing machine, in combination, an agitator shaft, a pinion secured thereto, a segmental driving gear adapted to be engaged with and disengaged from said pinion, a pivotal mounting for said segmental gear, a pitman for oscillating said gear having one end pivotally connected to said segmental gear at a point outwardly disposed from the gear axis and an eccentric mounting for the pivot of the gear permitting the gear to be moved into and out of driving relation with said pinion, said eccentric and the pivotal connection between the pitman and segmental gear causing the segmental gear to have a compound movement radially and tangentially of the pinion during the clutching operation.
- 60 8. In a washing machine, in combination, means for driving an agitator including a pinion, a segmental gear adapted to be engaged with and disengaged from said pinion, a pivotally mounted pitman pivotally connected to said gear eccentrically thereof for oscillating said gear, and means for shifting said gear with a compound movement around the pivotal axis of said pitman and around the pivotal connection of said pitman to said gear.
- 70 9. In a washing machine, in combination, means for driving an agitator including a pinion, a segmental gear adapted to be moved into and out of engagement with said pinion, means for oscillating said gear, and means for moving said gear into engagement with said pinion with a movement substantially radial of the pinion during the first part of the engaging operation and with a movement substantially tangential of the pinion during the latter part of the engaging operation.
- 80 In testimony whereof I have affixed my signature.
- ALBERT R. HAAG.
